CLAIM

The ornamental design for a condensate neutralizer device, as shown and described.

DESCRIPTION

FIG. 1 is a top right front view of a condensate neutralizer device.

FIG. 2 is a bottom left rear view thereof.

FIG. 3 is a top view thereof.

FIG. 4 is a bottom view thereof.

FIG. 5 is a front view thereof.

FIG. 6 is a rear view thereof.

FIG. 7 is a right side view thereof; and,

FIG. 8 is a left side view thereof.

The rectangular and circular features disposed on the front portion of the right side of the condensate neutralizer device as shown in FIGS. 1 and 7, the circular features disposed on the lower portion of the front of the condensate neutralizer device as shown in FIGS. 1 and 4-8, the combined rectangular and circular features disposed on the bottom portion of the front support as shown in FIGS. 2 and 4, the semi-circular opening disposed on the bottom surface of the condensate neutralizer device as shown in FIG. 2, the two ports disposed on the rear of the condensate neutralizer device as shown in FIGS. 2-4 and 6-8 and the broken lines shown throughout the views represent the portions of the design that form no part of the claim.
